INDICATING FUSE PLUG

Filed April 16, 1930

OTTO W. FELDMANN,
INVENTOR

BY *Victor J. Evans*

ATTORNEY

WITNESS -
UNITED STATES PATENT OFFICE

OTTO W. FELDMANN, OF RICHMOND HILL, NEW YORK

INDICATING FUSE-PLUG

Application filed April 16, 1930. Serial No. 444,803.

This invention relates to electric fuse plugs and more particularly to a fuse plug of the self-indicating type.

The primary object of the invention is to provide a self-indicating fuse plug which can be economically manufactured and which is very efficient for its practical purposes of indicating a burned out or blown fuse in an electric circuit.

Another object of the invention is to provide a fuse plug of the above type in which the fuse is normally held under tension, so that breaking will be facilitated particularly when the overload in the electrical circuit is insufficient to melt the fuse, so that the fuse element will break without the formation of globules during burning of the fuse slightly below the fuse element's melting point.

Still another object is to construct the fuse so that the indicating element may be forcibly ejected by means of an ejecting spring, when the fuse has been ruptured, the indicating element being normally held in non-indicating position by a retaining spring of less tension than the ejecting spring.

A further object is to construct the interior of the fuse body with receptacles or chambers for the ejecting spring and retaining spring so that the fuse element will not be in danger of being sheared off by the ejecting spring, in case the spring is turned during the manufacturing operation.

A still further object is to construct the fuse so that assembly of the same will be facilitated during manufacture, the construction being such that the fuse element may be inserted first, and the ejecting spring subsequently hooked on to the fuse as the parts are assembled.

Yet another object is to construct the indicator so that there will be no possibility of the same jamming or failing to indicate when a fuse has blown, the outer cap or other part of the fuse body being preferably equipped with guiding means for the indicator so that the same will be positively ejected.

Other objects are to simplify and improve the construction of fuse plugs generally and reduce the cost of manufacture thereof.

Other objects and advantages of the inven-

tion will be hereinafter specifically pointed out or will become apparent, as the specification proceeds.

With the above indicated objects in view, the invention resides in certain novel constructions and combinations and arrangement of parts, clearly described in the following specification and fully illustrated in the accompanying drawings, which latter show embodiments of the invention as at present preferred.

In said drawings:

Fig. 1 is a bottom plan view of the plug;

Fig. 2 is a side elevation of the plug, bottom end up;

Fig. 3 is a longitudinal sectional view, substantially on the line 3—3 of Fig. 2 looking in the direction of the arrows, showing the interior parts in normal position.

Fig. 4 is a view similar to Fig. 3 showing the indicator in its ejected position; and

Fig. 5 is to a top plan view of the plug.

The self-indicating fuse plug 10 in the present instance includes a body portion 11 preferably formed of porcelain or other insulating material, this body portion preferably having a generally downwardly tapering contour, to facilitate manufacture of the same. This body 11 is provided with an elongated axial fuse chamber 12; and a transverse opening 13 leads from the fuse chamber 12 to the outer side of the plug body 11. The lower end of the plug body 11 is provided with a center contact 14; and to the neck portion 15 of this center contact 14, which neck portion preferably extends into the fuse chamber 12, the fuse element 16 is attached. This fuse element 16 preferably consists of a strip or the like of fusible material. The fusible element 16 is positioned in the chamber 12 so that a loop portion 17 is formed adjacent to the transverse opening 13; and the free end of the fuse element 16 is passed through this opening to the outer side of the plug body 11 as seen at 18. This free end of the fuse element is secured in place at the outer side of the body 11 by means of the shell 19 which is formed with screw threads 20 corresponding to the screw threads 21 formed about the body 11. Any excess length of the

5 fuse element projecting beyond the lower end of the shell as indicated at 18 is removed, and the opposite ends of the fuse may be soldered to the center contact 14 and shell 19. Thus, 10 as stated hereinabove the fuse element 16 is put in place as the first step in the assembly of the parts of the plug; that is, before the indicator or the indicator ejecting means are inserted. The shell 19 and center contact 14 serve to place the fuse element 16 in the 15 circuit in the manner customary with fuses of the plug type.

10 Means are provided to positively indicate the breaking of the fuse due to overload, short circuiting or the like in the electrical circuit; 15 and in this instance said means include an indicator 22 having a head portion 23 and a stem 24. This indicator 22 is positioned in an enlarged bore 25 formed at the outer end of 20 the plug body 11, this outer end of the plug body being closed by a cap 26, this cap 26 having a rearward portion 27 preferably turned over the outer rim 28 of the plug body during the course of manufacture. To secure 25 the cap in place against rotation relative to the plug body 11, the outer rim 28 of the plug body may be provided with a plurality of indentations 29 into which the rearwardly turned portion 27 of the cap 26 may be de- 30 pressed; and the outer surface of the portion 27 may be provided with a knurled surface to facilitate insertion of the plug into and its removal from, its socket. The body 11 is also preferably provided with substantially 35 similar indentations 39 into which portions of the shell 29 may be pressed, to securely hold the shell in place. The cap 26 in this instance has an axial aperture 30 adapted to receive the end of the stem 24; and the portion 40 of the cap 26 forming the annular wall of the aperture 30 is preferably turned inwardly as seen at 31 to afford a guide for the stem 24 whereby the stem is maintained in proper position for positive ejection, and is guided 45 during its travel during the ejecting movement. The indicator 22, in the normal position of the interior parts of the plug, rests against a shoulder 32 formed at the base of the chamber 25, and the indicator is retained 50 in this normal position by means of a coil spring 33 adapted to act between the inner side of the cap 26 and the outer side of the head 23 of the indicator.

55 Means are provided to eject the indicator upon breaking of the fuse, and in this instance said means include an ejector spring 34 provided at the inner side of the head portion 23 of the indicator, this ejector spring 34 being positioned in a bore 35, this bore 35 being of 60 smaller diameter than the outer chamber 25, and of slightly greater diameter than the fuse chamber 12. Thus a shoulder 36 is formed at the base of the ejector spring chamber 35, against which the ejector spring is adapted 65 to bear. The ejector spring is provided at

its lower end with a hook portion 37 adapted to be hooked over the loop portion 17 of the fuse element 16. The combined tension of the retaining spring 33 and fuse element 16 is just sufficient to overcome the force of the 70 ejector spring 34, which as will thus be understood is of greater tension than the retaining spring 33.

75 When the fuse element 16 has become weakened due to an overload or short circuiting of an electrical circuit, whether such weakening is only partial, or a complete fusing or melting of the fuse element 16, the ejector spring 34, released from the fuse, and being of greater tension than the retaining spring 80 33, will forcibly eject the indicator 22 from the position seen in Fig. 3 to the position shown in Fig. 4. The stem 24 will thus project beyond the outer surface of the cap 26, where the same can be readily seen, or felt, to 85 indicate the fuse that has burned or blown. The outer end of the stem 24 may be provided with suitable insignia 38, which may be the manufacturer's trade-mark or any other desired device. 90

95 An important feature of the present construction is the facility of assemblage of the parts. As already stated the fuse element 16 is first put in place. Then, the ejector spring 34 is inserted in the chamber 35, and the hook portion 37 at the lower end of the ejector spring is hooked over the looped portion 17 of the fuse element. The retaining spring 33 is then applied around the stem 24, and the cap 26 is then put in place and secured. The 100 arrangement of the shoulder 36 and transverse passage 13 is such that the fuse element 16 is not likely to be sheared off during the assembly of the parts. The attachment of the fuse element 16 as the first step in the 105 manufacture is a distinct advantage over former types of fuses since it eliminates the difficulty usually attendant upon inserting the fuse element as the last step in assembling the parts. 110

115 The indicator 22 is made of insulating material so that there is no danger of short-circuiting or electrical disturbance within the fuse, or at the exterior thereof. Also, it is to be understood that while I preferably insert the fuse element as a first step in assembling the parts, the fuse elements may also be inserted last if desired. Furthermore, the transverse opening 13 is desirably formed at a cut out portion of the shoulder 36, so that the insertion of the fuse element is thereby facilitated. 120

125 The hereinbefore described construction admits of considerable modification without departing from the invention; therefore, it is the wish not to be limited to the precise arrangements shown and described, which are as aforesaid, by way of illustration merely. In other words the scope of protection contemplated is to be taken solely from the appended 130

claims, interpreted as broadly as is consistent with the prior art.

What I claim is:

1. A self-indicating fuse including a body portion formed of insulating material said body having a bore and a transverse fuse opening extending through a wall of said body, a center contact at the base of said body in axial alignment with said elongated bore, 5 a fusible element having one of its ends secured to said center contact, the opposite end of said fusible element extending through said transverse opening and being secured at the outer side of said body, an indicator at 10 the forward end of said body, an ejector spring normally compressed between said indicator and said shoulder, said ejector spring having a portion normally in engagement with said fusible element, and a retaining 15 spring at the front of said indicator head. 20

2. A self-indicating fuse including a body portion formed of insulating material said body having an internal bore and a transverse fuse opening extending through a wall 25 of said body to said bore, a center contact at the base of said body in axial alignment with said elongated bore, a shell secured at the outer side of said body, a fusible element having one of its ends secured to said center 30 contact, the opposite end of said fusible element extending through said transverse opening and being secured between said shell and said body, an indicator at the forward end of said body, a resilient ejector member normally compressed behind said indicator, said 35 ejector normally in engagement with said fusible element, a retaining spring at the front of said indicator and an outer cap at the front of said body, said cap having an axial opening for said indicator when ejected by rupture of said fusible element. 40

3. A self-indicating fuse including a body portion formed of insulating material said body having an elongated plural diameter 45 bore and a transverse fuse opening extending through a wall of said body, a center contact at the base of said body in axial alignment with said elongated bore, a screw threaded shell secured at the outer side of said body, a 50 fusible element having one of its ends secured to said center contact, the opposite end of said fusible element extending through said transverse opening and being secured between said shell and said body, said bore including a larger diameter chamber forming 55 a shoulder forward of said elongated chamber, an indicator at the forward end of said body, an ejector device between said indicator and said shoulder, said ejector device normally secured to said fusible element, a retaining spring at the front of said indicator head, an outer cap at the front of said body, said cap having an axial opening, and the wall of said opening 60 including an inwardly extending guiding rim for said stem when ejected by rupture of said fusible element. 65

extending guiding rim for said stem when ejected by rupture of said fusible element.

4. A self-indicating fuse including a body portion having a bore and a transverse fuse opening extending through a wall of said body, a center contact on said body, a shell secured at the outer side of said body, a fusible element having one of its ends secured to said center contact, the opposite end of said fusible element extending through said transverse opening and being secured between said shell and said body, an indicator forward of said fusible element, an ejector spring normally compressed behind said indicator, said indicator including a head and a stem, said ejector spring having a portion normally in engagement with said fusible element, a retaining spring at the front of said indicator head, an outer cap at the front of said body, said cap having an axial opening, the wall 85 of said opening including an inwardly extending guiding rim for said stem when ejected by rupture of said fusible element. 90

5. A self-indicating fuse including a body portion formed of insulating material, said body having an elongated plural diameter bore and a transverse fuse opening extending through a wall of said body, a center contact at the base of said body in axial alignment with said elongated bore, a screw 95 threaded shell secured at the outer side of said body, a fusible element having one of its ends secured to said center contact, the opposite end of said fusible element extending through said transverse opening and being secured between said shell and said body, said fusible element including a looped portion, said bore including a larger diameter chamber forming a shoulder forward of said elongated chamber, an indicator at the forward 100 end of said body, an ejector spring normally compressed between said indicator and said shoulder, said indicator including a head and a stem, said ejector spring having a hooked portion at its forward end normally 110 in engagement with the looped portion of said fusible element, a retaining spring at the front of said indicator head, an outer cap at the front of said body, said cap having an axial opening, and the wall of said opening 115 including an inwardly extending guiding rim for said stem when ejected by rupture of said fusible element. 120

In testimony whereof I hereby affix my signature.

OTTO W. FELDMANN.
